Inventor:

Isaac Fenno.

By Crosby & Longby Atty.

UNITED STATES PATENT OFFICE.

ISAAC FENNO, OF BOSTON, MASSACHUSETTS.

HORSESHOE.

SPECIFICATION forming part of Letters Patent No. 289,402, dated December 4, 1883.

Application filed January 29, 1883. (No model.)

To all whom it may concern:

Be it known that I, ISAAC FENNO, of Boston, county of Suffolk, and State of Massachusetts, have invented an Improvement in Horseshoes, 5 of which the following description, in connection with the accompanying drawings, is a specification, like letters on the drawings representing like parts.

My invention, relating to horseshoes, has for its object to provide means for readily attaching shoes of different character to the horse's foot. In some climates the surface of the ground will be for a short time covered with ice, requiring long sharp calks on the horse's shoe, 15 and then in a few days the ice will have disappeared, leaving the ground bare and frozen, and requiring a shoe without calks for the comfort of the horse. It results from this that, with the ordinary method of attaching shoes, the 20 horse would have to be frequently reshod, or else would have to wear unsuitable shoes during a large portion of the time. Detachable calks have been employed, but as yet without very great success.

25 My invention is embodied in a double shoe for each hoof, one shoe being permanently attached to the hoof by nails, or in any usual manner, and being called, for distinction the "permanent" shoe, and the other, which may 30 be termed the "wearing" or "detachable" shoe, and which will be varied according to the condition of the roads, being adapted to be quickly attached to or removed from the said permanent shoe, so that it is possible, by having 35 two or three different kinds of wearing-shoes, to prepare the horse at a moment's notice for any kind of road. The permanent shoe is provided at its toe end with a dovetailed socket 40 extending back a short distance from the toe end into the body of the shoe, while the wearing-shoe is provided with a corresponding dovetailed projection, which, by sliding the said shoe back on the permanent shoe, enters the said recess, thus securely fastening the two shoes 45 together at their toe end. The two shoes are provided at or near their heel end, one with engaging projections and the other with corresponding sockets, which are brought into engagement by the movement of the detachable 50 shoe toward the permanent shoe, and which, when engaged, prevent any sliding movement of one shoe upon the other, and consequently

prevent the disengagement of the dovetail at the toe end of the shoe. The heel end of the detachable shoe is fastened to the permanent 55 shoe by a wire twisted around the two shoes, which prevents the disengagement of their projections and sockets, and thus securely fastens the two together, the strength of the union between the shoes depending on the projections, 60 rather than on the fastening device, which, by merely supporting the weight of the shoe, keeps the said projections in position.

I am aware that it is not new to have a detachable wearing-face for a horseshoe, and do 65 not broadly claim such construction.

Figure 1 is an under side view of a horseshoe embodying this invention, a portion of the detachable shoe being broken away; Fig. 2, a front elevation thereof; Fig. 3, a section 70 on line *x-x*, Fig. 1, of the heel portion of the shoe; Fig. 4, an end elevation of the heel portion of the shoe, and Fig. 5 is a cross-section in the plane of line *y-y*, Fig. 3.

The main or permanent shoe *a*, attached to the hoof in any usual manner, is provided with a dovetail socket, *2*, in its forward or toe portion, extending back a short distance from the front of the shoe, as shown in dotted lines, Fig. 1, and the said permanent shoe is also provided with one or more engaging projections, *b*, 80 near the heel end of each side of the shoe. The detachable or wearing shoe *c* (shown in this instance as provided with long sharp calks *d* for use upon icy roads) has a dovetail projection, *e*, at its toe end, fitted to the socket *2* of the shoe *a*, and has holes or sockets *4* in its heel portions, properly located to receive the projections *b* when the shoes *a-c* coincide. Thus by placing the shoe *c* slightly forward of the 90 shoe *a* and sliding it backward thereon, the dovetail *e* will be carried into its socket *2*, and then by pressing the shoe *c* against the shoe *a* the projections *b* will enter the sockets *4*, thus preventing the withdrawal of the dovetail *e* 95 from its socket, so that the two shoes are securely fastened together at their toe ends, and retained in coincidence throughout; and in order to securely fasten the shoe *c*, it is only necessary to prevent its heel end from dropping 100 far enough to disengage the projections *b*. A fastening device for this purpose is shown as consisting of a wire, *h*, twisted around the coinciding heels of the two shoes, just in front

of the heel-calk, or preferably, as shown, passing through a hole, 5, in the heel-calk, which is grooved at its side, as shown in Fig. 5, to receive the twisted ends of the said wire fastening *h*.

The shoes *a* will preferably have a washer, *n*, inserted between them, which may consist of leather or rubber or felting, and, if desired, may extend across the bottom of the hoof to prevent the balling of snow therein.

When desirable, on account of a change in the weather or condition of the roads, the fastenings *h* and the shoe *c* may be removed by a coachman or teamster, and another shoe having similar projections and recesses for attachment to the shoe *a*, but a different lower or

wearing face suitable for the new condition of the roads, may be attached to the shoe *a* in a similar manner.

I claim—

The permanent shoe *a*, having the dovetail socket 2 and projections *b b*, combined with the detachable shoe *c*, having the dovetail projection *e* and sockets *4 4*, and the fastening-wires, substantially as shown and described.

In testimony whereof I have signed my name to this specification in the presence of two subscribing witnesses.

ISAAC FENNO.
